UNITED STATES PATENT OFFICE.

GUSTAV F. HOCHRIEM, OF CHICAGO, ILLINOIS, ASSIGNOR TO RHODES-HOCHRIEM MANUFACTURING CO., OF CHICAGO, ILLINOIS, A CORPORATION OF ILLINOIS.

COIN SELECTOR.

Application filed January 2, 1924. Serial No. 683,937.

The present improvements relate to means for selecting or separating coins according to their respective sizes. A useful application thereof is in connection with coin-controlled mechanisms in which it is desirable to operate the device only with coins of a predetermined value and where coins of different values have different sizes. For instance there is a material difference in the 10 diameters respectively of five-cent pieces and one-cent pieces.

Where a given machine is intended to be operated by a five-cent piece or "nickel," it frequently happens that persons will seek 15 to operate the machine with a one-cent piece or "penny," so called. An object of the present improvements is to provide means for rejecting the one-cent piece in such case while retaining the five-cent piece 20 for operation of the machine. It is a further object to provide coin-selecting or separating means for such and analogous uses according to which the selective mechanism may be readily adjusted so as to retain 25 coins of all denominations or sizes for operation of the machine, valuable in instances where the machine is intended to be operated by a one-cent piece and persons not having that coin are disposed to deposit a 30 coin of a larger denomination in the device to purchase the commodity or derive the benefit of the transaction, whatever it may be that the machine is intended to accomplish.

35 The invention has application to other uses and may be variously embodied in view of the teachings herein given.

In the accompanying drawings, which 40 form a part of this specification, Figure 1 is a face view of a coin chute showing the improved construction in a highly advantageous form; Fig. 2 is an edge view of the parts of Fig. 1, portions thereof being broken away in medial longitudinal section, 45 and Fig. 3 is a cross section on the line 3—3 of Fig. 1.

The coin chute body is shown as being of 50 tubular construction, substantially rectangular in cross view, relatively wide, and may be considered as being formed of sheet metal. A portion of the housing of the coin-controlled machine is shown at 10 with an opening 11 leading into the hollow interior of the chute.

55 The chute is shown as being first directed

downward at the part 12 and then extends downwardly and forwardly throughout the section 13. At 14 a bend is shown in the chute and the section 15 extends vertically therefrom and at a materially great angle 60 with respect to the line of direction of the section 13. From section 15 coins may be discharged upon a plate 16 pivotally mounted at 17 and constituting part of tripping mechanism for the coin-controlled device, 65 and the coin may thereupon fall into the coin receptacle 18 understood to be within the housing of the machine. It is not necessary here to go into any details of such coin-controlled mechanisms as there is a 70 large variety of them at the present time well known and the present improvements have to do only with means for selecting a coin or coins adapted to operate or control the device. 75

Just below the bend at 14 and at the upper end of the section 15 there is provided an opening 20 in what may be termed the front wall of the chute. In my practice this opening is of such width that a one-cent piece may pass therethrough, but is of insufficient width for the escape of a coin of materially larger diameter, for instance a five-cent piece. The vertical length or height of the opening 20 may vary within wide limits, the principal consideration being that it be great enough to permit the smaller coins to pass through under all conditions of practice. This opening at 20 is defined at the sides by portions 21 of the chute overlying its hollow interior to some extent and constituting deflecting means for coins of the larger diameter. From Fig. 2 it will be seen that a coin as 23 sliding on its side downwardly and forwardly will continue substantially in that line or path of travel, for a short distance at least, beyond the lower end of the section 13 at 24, and since the opening 20 is in line with the path of movement of the descending coin as 23 100 the coin will be projected through the opening 20, and away from the chute, if the coin be small enough to pass through the opening 20. If the coin should be directed straight for the opening 20 it would pass through substantially without touching the deflecting means 21, but ordinarily the coin will be a little more towards one edge of the chute, as illustrated by the coin 25 in Fig. 105

110

105 The coin will strike the def-
lecting means 21, but ordinarily the coin will be a little more towards one edge of the chute, as illustrated by the coin 25 in Fig. 1, in which case the coin will strike the de-

reflecting means at that side; but since the diametrically-opposite peripheral portion of the coin is then materially far removed from the other deflecting element 21 the gravitational projection causes the coin to proceed forward and through the opening with a sort of spilling-out movement, and the result is that invariably the coin will be projected out of the chute. It will be clear that 10 should the chute section 13 be inclined laterally so that coins would always descend traveling against a given edge wall of the chute the opening as 20 would not need to be the full width of the coin.

15 In the case of the larger coin, for instance a five-cent piece, the edge walls of the chute are so related to the deflecting means 21 that no matter whether the larger coin be directed in a path straight down the middle 20 of the chute 13 or at one side thereof both of the deflecting elements 21 will engage peripheral portions of the coin and retain it within the chute, the result being that it will descend further and operate the coin-controlled mechanism. In my practice the width of the coin chute at the section 13 is only a little greater than the diameter of a five-cent piece while the width of the opening 20 is only slightly greater than the diameter 30 of a one-cent piece.

I also provide a readily movable closure or obstructing means for the opening 20 which is illustrated in the form of a sleeve 26 slidably mounted upon the section 15 of the chute whereby it may be moved upward as shown by dotted lines so as to close the opening 20. Means for holding the closure 26 in position are shown as a small indentation of the metal at 27 made by a prick-40 punch and being so positioned as to engage the edge portion of the front wall of the chute at 28 at the opening 20 when the closure is moved upward. This lower edge at 28 is preferably slanted off inward so 45 that under no circumstances will a coin catch thereat. When the closure is moved

upward into its dotted-line position all of the coins inserted at the entrance opening 11 will be deflected into the chute section 15.

I contemplate as being included in these 50 improvements such changes, modifications of and departures from what is herein specifically illustrated and described as fall within the scope of the appended claims.

I claim:

1. A tubular coin chute having a flat sliding surface arranged to guide coins moving gravitationally downward therein sliding on their sides respectively and having means for deflecting the coins into another path of movement, said deflecting means defining an opening in the downward path of movement of the coins through which relatively small coins may pass out of the chute while larger coins are deflected into another path 65 of movement, and slidably closure means readily movable into position to obstruct said opening.

2. A coin chute having a downwardly-and-forwardly extending section and a lower 70 section downwardly extending therefrom at an angle to the line of direction of the first-mentioned section, there being an opening in the forward wall of said lower section close to where the two sections come together and 75 in the line of movement of a coin sliding through the first-mentioned section, the chute having coin-retaining means at the sides of and defining the width of said opening and being adapted to retain in the chute 80 coins of a given diameter, the construction and arrangement being such that coins of a given smaller diameter passing through the first-mentioned portion will be discharged through said opening out of the chute, and 85 a slidably sleeve provided with an indentation for obstructing said opening to retain in the chute coins of the smaller diameter, said indentation cooperatively engaging one edge of the coin retaining means defining 90 the opening.

GUSTAV F. HOCHRIEM.
